CARTRIDGE FUSE

Earl W. Wells, St. Claire Shores, Mich.

Application October 31, 1945, Serial No. 625,720

1 Claim. (Cl. 200—131)

1

My invention relates to a new and useful improvement in a fuse and has for its object the provision of a renewable fuse which will be simple in structure, economical of manufacture, durable, compact, easily and quickly assembled and highly efficient in use.

Another object of the invention is the provision of a renewable fuse so constructed and arranged that it is ventilated while in use and thus excessive heating of the fuse plug is avoided.

Another object of the invention is the provision of a renewable fuse so constructed and arranged that heat generated within the plug may escape while at the same time the passage of a flame from within the plug is prevented.

Another object of the invention is the provision of a renewable fuse which may be easily and quickly taken apart in order to replace the fusible material.

Another object of the invention is the provision of a renewable fuse having an enclosing housing which may be taken apart and easily and quickly placed together and locked in operative position.

Other objects will appear hereinafter.

It is recognized that various modifications and changes may be made in the detail of structure illustrated and it is intended that such shall be embraced within the scope of the claims which form a part of this application.

Forming a part of this application are drawings in which:

Fig. 1 is a longitudinal central sectional view of the invention.

Fig. 2 is a longitudinal central vertical sectional view of the invention taken at right angles to that shown in Fig. 1.

Fig. 3 is a perspective view of the various parts of the invention in their separated relations.

Fig. 4 is a view taken on line 4—4 of Fig. 1.

Fig. 5 is a sectional view taken on line 5—5 of Fig. 1.

Fig. 6 is a longitudinal central sectional view showing a modification.

Fig. 7 is a sectional view taken on line 7—7 of Fig. 6.

Fig. 8 is a fragmentary central vertical sectional view showing the invention modified for use on a ferrule type fuse.

Fig. 9 is a fragmentary central vertical sectional view of form shown in Fig. 8 illustrating the opposite end of fuse.

Forming a part of the enclosing housing is a cylindrical tube or barrel 12 on one end of which is fixedly attached a ferrule or a metallic cap 13 having a central circular opening 14 formed therein radiating outwardly from which at dia-

2

metrically opposite points are the slots 15. A retaining or supporting body 16 of suitable insulating material is adapted to be enclosed by the tube or barrel 12 which is also made from suitable insulating material. A contact plate 17 is provided with the reduced portion or neck 33 which is projected through the opening 34 formed in the end block 35 of the supporting member 16. Embedded in the member 16 is a nut-forming member 44. A bolt 18 is projected through the neck 33 and threaded into the nut-forming member 44. A spring washer 19 is positioned under the head of the bolt. This bolt 18 also projects through the terminal portion of the fuse strip 24 and through a retaining clip 45 so that when the bolt 18 is tightened the retaining clip 45 will press the end of the fuse strip 24 into close engagement with the reduced portion 33 of the contact plate 17. Threaded into a similar nut-forming member 44A is a bolt 22 beneath the head of which is positioned a spring washer 23. This bolt 22 also projects through a retaining clip 45, the terminal portion of the fuse strip 24 and the reduced neck 36 of a contact plate 21 so that the two contact plates 21 and 17 are thus electrically connected to the fuse strip 24. Positioned beneath the fuse strip 24 is a recess 20 which is formed in the supporting member 16. The neck 36 projects through a suitable slot 30 formed in the end block 37 of the supporting member 16. The ferrule or metallic cap is secured to the end block 37 by means of the screws 38.

Formed in the periphery of the barrel or tube 12 is a groove 30 communicating through the openings 31, which are preferably diametrically opposite each other, with the interior of the tube or barrel 12. This peripheral groove 30 is covered by the cap or ferrule 13 and formed in the covering portion of the ferrule are openings 32, which are preferably diametrically opposite each other and rotated 90 degrees to the opening 31. These openings 32 are in registration with the peripheral groove 30. Fixedly mounted on the tube or barrel 12 is a metallic ring 26 which serves to cover the peripheral groove 27 formed on the barrel or tube 12. Openings 28, which are also preferably diametrically opposite each other serve to establish communication of this groove 27 with the interior of the tube or barrel 12. Openings 29, which are preferably diametrically opposite each other and rotated 90 degrees to the location of the openings 28 are formed in the ring 26 and are in registration with the groove 27. Thus the interior of the fuse plug when assembled as shown in Fig. 1 is always in com-

munication with the atmosphere. This would permit heat generated within the housing to escape through the openings and grooves so that the fuse would be prevented from excessive heating. When a flash occurs and a flame develops within the housing this flame would be prevented from escaping as after passing through the openings 28 or 31 the flame would have to travel around the peripheral groove at least a quarter revolution and in the restricted space the flame would become extinguished.

In order to assemble the structures a simple operation is necessary. The contacts 21 and 27 would be connected together with the fuse strip 24 and the supporting member 16 as shown in Fig. 1. And in this position the housing may then be slipped over so as to cover the parts and in doing so it is necessary to rotate the tube or barrel 12 until the slots 15 register with the contact plate 17. When in this position the barrel or tube 12 may be slid onto the assembled structure into the position shown in Fig. 1. By rotating the tube 12 90 degrees the end wall of the ferrule or cap 13 rides behind the contact plate 17 and the member 12 is thus locked in position. Consequently, in order to gain access to the interior of the fuse it would be but necessary to rotate the tube or barrel 12 90 degrees in either direction from the position shown in Fig. 4 whereupon, the tube or barrel 12 could be moved axially off of the structure. When the covering tube or barrel 12 is removed access to the fuse strip is of course afforded and an easy and quick replacement of the fuse strip may be made when necessary.

In Fig. 6 I have shown a slight modification of the structure. This modification however, relates only to the method of attaching the fuse strip 39. This fuse strip is provided with a slot 40 in one end to provide a bifurcated structure which may engage around and under the head of the bolt 42. The opposite end of the fuse strip is provided with a hook which may engage around and under the head of the bolt 43. With this structure it would not be necessary to remove the bolt entirely when replacing a fuse strip.

In Fig. 8 and Fig. 9 I have shown a further modification in which the invention may be utilized in connection with a ferrule type fuse. In this structure I utilize a housing or tubular enclosure 12A corresponding to the part 12 shown in Fig. 1. The supporting body 16A is provided at its end with a projection 37A and at its opposite end with the projection 35A. Embracing one end of the tubular housing 12A is a metallic ferrule 71 having the inward projection 72 embedded in the housing 12A so that these parts are in fixed relation. This ferrule or cap 71 is provided with the outwardly projecting internally threaded neck 73 which is adapted to thread upon the threaded stud 74 projecting outwardly from the metal plate 75 which is held in position by the bolt 76 which serves to clamp the fuse strip 27A against the part 75. At the opposite end I provide a cap or ferrule 77 having an opening 78 formed centrally therein through which the reduced portion 79 extending outwardly from the plate 81 projects. This reduced portion is upset to provide the head 80. The plate 81 is held in clamping relation to the fuse strip 27A by the bolt

82. With this type of fuse the contacts are of course made at the ferrule ends ferrules 71 and 77 contacting spring retainers in a manner which is well known. In order to dis-assemble the structure it is but necessary to grip the ferrule 71 in the hand and then rotate the housing 12A until the neck 73 dis-engages from the threaded stud 74 whereupon the housing 12A may be withdrawn to allow ready access to the renewable fuse strip.
- 10 With a fuse constructed in this manner a highly efficient apparatus is afforded and one which will not develop excessive heat and which on account of remaining cool will be of longer life. It is believed obvious that the structure is such that 15 assembling may be easily and quickly effected and that a fuse strip may be removed and replaced with ease.

What I claim as new is:

- A fuse of the class described, comprising: a 20 supporting member of insulating material having a recess formed therein intermediate its ends; a contact plate secured to each end of said supporting member and projecting outwardly therefrom, each of said contact plates being narrowed 25 intermediate its ends to provide a narrow neck; a fusible fuse strip connecting the inner ends of said contact plates electrically and spanning said recess; a tubular housing for enclosing said supporting member and said fusible strip and provided 30 with a peripheral groove communicating through an opening with the interior of said housing; a cup-shaped closure for one end of said housing and adapted for embracing the same, said closure having in its side wall an opening 35 registering with said groove and out of alignment with the opening through said housing, said cup-shaped closure having a central opening formed in its base sufficiently large for receiving said neck and provided with radially projected slots extending outwardly therefrom diametrically opposite each other sufficient for passage of the outer end of the contact plate therethrough, relative rotation of said contact plate and said closure effecting a movement of said 40 contact plate out of alignment with said radially outwardly projecting slots for securing said closure in position on said tubular housing and retaining the opening in said closure out of registration with the opening in said tubular housing 45 and preventing axial movement of said tubular housing relatively to said supporting member.
